(57) **CLAIM**

The ornamental design for a sunglasses holder for car, as shown and described.

DESCRIPTION

FIG. 1 is a Perspective view of a sunglasses holder for car showing my new design;

FIG. 2 is another perspective view thereof;

FIG. 3 is a Front view thereof as shown in FIG. 1;

FIG. 4 is a Back view thereof as shown in FIG. 1;

FIG. 5 is a Right-side view thereof as shown in FIG. 1;

FIG. 6 is a Left-side view thereof as shown in FIG. 1;

FIG. 7 is a Top view thereof as shown in FIG. 1; and,

FIG. 8 is a Bottom view thereof as shown in FIG. 1.

The broken lines are only for environmental purposes and form no part of the claimed design.
